HEATER FOR STARTING DIESEL ENGINES

Filed April 19, 1939

UNITED STATES PATENT OFFICE

2,229,714

HEATER FOR STARTING DIESEL ENGINES

Gottfried Wirrer, Plainfield, N. J., assignor to
Mack Manufacturing Corporation, Long Island City, N. Y., a corporation of Delaware

Application April 19, 1939, Serial No. 268,681

6 Claims. (Cl. 123—179)

The present invention relates to starting devices for Diesel engines and embodies, more particularly, an improved mechanism by means of which the air temperature, upon starting, is elevated in order that the final compression temperature of the air and fuel charge of the engine may be above the ignition temperature of the fuel, regardless of the external conditions at the time of starting.

10 Inasmuch as the air in the cylinder of a Diesel engine must be compressed to a temperature above the ignition temperature of the fuel in order to start the engine, the initial air temperature is an important factor in easy starting. 15 The effect of the initial air temperature upon the final compression temperature will be readily apparent when it is recalled that the final compression temperature depends upon the ratio of compression and the initial air temperature. 20 The electric heater plugs or elements in the inlet manifold that have heretofore been used to pre-heat the air before it enters the cylinder have not proved entirely satisfactory, and an object of the present invention is to improve the 25 starting characteristics of a Diesel engine by pre-heating not only the air but also the inlet manifold and the interior of the combustion space during the starting operation. This results in a great improvement in the starting operation over the operation of devices now available.

20 A further object of the invention is to provide an effective mechanism by means of which the starting of Diesel engines is facilitated and requiring only a very simple operation to render 35 effective.

25 A further object of the invention is to provide a device of the above character which is set in operation by a predetermined action and then requires no further attention upon starting of 40 the engine.

Further objects of the invention will be apparent as it is described in greater detail in connection with the accompanying drawing, wherein:

Fig. 1 is a diagrammatic illustration of a mechanism embodying the present invention;

Fig. 2 is a view in section taken on the line 2—2 of Fig. 1 and looking in the direction of the arrows;

Fig. 3 is a view in section taken on the line 50 3—3 of Fig. 2 and looking in the direction of the arrows.

Fig. 4 is a partial view in section, taken on the line 4—4 of Fig. 1 and looking in the direction of the arrows.

55 Referring more particularly to the above draw-

ing, an inlet manifold is shown at 10 and is provided with air from a passage 11, at one side of which is formed a threaded boss 12. A fitting 13 is secured to the boss, as illustrated in Fig. 2, and this fitting is adapted to receive a nozzle 14 which is illustrated in enlarged section in Fig. 3. The passage 11 is also formed with a baffle 15, the purpose of which will be described in greater detail hereinafter. The baffle is formed of two plates spaced upon opposite sides of the 10 axis of the inlet duct 11.

A spark plug 16 is mounted so that its terminals extend into the passage 11 and lie upon one side of the baffle 15. The spark plug is connected by means of a wire 17 to an ignition coil 18 having a vibrator 19. One end of the primary winding of the ignition coil is grounded at 20 and the other end is connected by a wire 21 to a battery 22. The starting motor is shown at 23 and is connected to wire 21 by means of wire 24 20 and grounded by means of wire 25. The starting switch is illustrated at 26 and is connected to the battery by means of a wire 27 and grounded by means of a wire 28.

The nozzle 14 is connected to a fuel tank 29 25 by means of a duplex tubing 30 and an air pump 31 is also connected to the fuel tank 29 through a tubing 32. As illustrated in Fig. 3, the duplex tubing 30 consists of an outer tube 33 and an inner tube 34. The outer tube communicates 30 with the top of the fuel tank 29 and is secured to the nozzle 14 by means of a fitting 35 which is provided with a fluid tight bushing 36. The nozzle 14 is formed with a chamber 37 and passages 38 so that the air within the tubing 33 is 35 supplied to a chamber 39 which communicates with the nozzle aperture 40. The inner tubing 34 extends downwardly into the fuel tank 29 as indicated at 41 in order that the air pressure upon the top of the fuel created by the pump 40 31 may force the fuel into the tubing 34 where it is supplied to a chamber 42 and a passage 43 which directs the fuel through the air chamber 39 and to the aperture 40. A filter cap 44 and screen 45 may be provided for replenishing the 45 fuel in the fuel tank 29.

The head or cap 46 of the nozzle 14 is mounted by means of threads in order that it may be manipulated to meter the fuel and air in a desired fashion.

It will thus be seen that air pressure from the pump 31 forces the fuel oil and air from the tank 29 through the respective tubes 34 and 33 to the nozzle 14. After the pump 31 is operated, the starting switch 26 is depressed to start the 55

engine. This simultaneously closes the circuit of the primary winding of the ignition coil which results in igniting the atomized fuel supplied through the fitting 13 by the resulting operation of the spark plug 16. The air entering the manifold carries the flame through the manifold and into the cylinders. The baffle 15 diverts a portion of the air taken in so that only a part thereof is used for the combustion of the 10 atomized fuel, the other portion of the air being taken into the cylinder to support the combustion of the fuel injected into the combustion chambers. This is illustrated schematically in Fig. 4. This baffle further provides a large 15 surface which will greatly increase the heating of the incoming air after the flame of the atomizer is extinguished.

In operation, the spray from the atomizer should be adjusted so that small globules will 20 be formed which will cling to the electrodes of the spark plug. The spark heats these globules to a high temperature and ignites them, the resulting burning of these globules igniting the fuel oil coming from the atomizer. If the fuel 25 oil at low temperature is atomized to a very fine degree, the spark will not ignite it, whereas, if the particles are too coarse, they will extinguish the spark. It, therefore, is essential that the atomized particles be such as to cling to the 30 electrodes as above described.

It will be observed that the device will stop 35 automatically as soon as the air in the tank leaks out through the atomizer. Inasmuch as all of the atomized fuel will burn, no fuel oil will be drawn into the engine.

While the invention has been described with 40 reference to the specific structure shown in the accompanying drawings, it is not to be limited save as defined in the appended claims.

I claim:

1. Starting device for internal combustion engines comprising, an air inlet manifold having an air inlet duct, a nozzle to supply fuel and air under pressure to the manifold in spray form 45 adjacent said inlet duct, a baffle plate extending along said manifold and partially across said inlet duct and means to ignite said fuel in the manifold whereby combustion of said fuel heats the incoming air and said baffle plate.

2. Starting device for internal combustion engines comprising an inlet manifold, a plate formed therein, means lying substantially in the plane of the plate to introduce fuel in spray 50 form into the manifold upon opposite sides of

the plate, and a spark plug in the manifold upon one side of the plate to ignite the said fuel.

3. Starting device for internal combustion engines comprising an inlet manifold, an air inlet duct on the manifold, a baffle plate in the manifold to divert a portion of the air entering from the inlet duct, means to introduce fuel in spray form into the manifold in the path of air entering the manifold from the inlet duct and not diverted by said baffle plate, and means on the 10 side of the manifold away from the inlet duct to ignite said fuel.

4. Starting device for internal combustion engines comprising an inlet manifold, an air inlet duct on the manifold, baffle plates in the manifold on opposite sides of the inlet duct to divert a portion of the air entering from the said inlet duct, means to introduce fuel in spray form into the manifold in the path of air entering the manifold from the inlet duct and not diverted 20 by said baffle plates, and means on the side of the manifold away from the inlet duct to ignite the said fuel.

5. A heater for internal combustion engines comprising a manifold pipe having an air inlet 25 branch projecting from one side thereof, an igniting device in said manifold pipe substantially opposite to said inlet branch, a baffle plate extending along said manifold pipe having one end disposed adjacent to said inlet branch to divert 30 a portion of the incoming air away from said igniting device, a fuel atomizer for directing a spray of fuel into said manifold pipe adjacent said one end of said baffle plate to be ignited and burned to heat said baffle plate and said 35 incoming air.

6. A heater for internal combustion engines comprising a manifold pipe having an air inlet branch projecting from one side and substantially intermediate the ends thereof, an igniting 40 device in said manifold pipe substantially opposite to said inlet branch, a pair of aligned baffle plates extending axially of said manifold pipe having their adjacent ends spaced apart and extending partially across said inlet branch to 45 divert a portion of the incoming air away from said igniting device toward the ends of said manifold pipe and a fuel atomizer for injecting a spray of fuel into said manifold pipe intermediate said igniting device and said inlet branch 50 and adjacent the inner ends of said baffle plates for ignition and combustion to heat said baffle plates and said incoming air.

GOTTFRIED WIRRER.
